UNITED STATES PATENT OFFICE

BLUFORD W. BROCKETT, OF CLEVELAND HEIGHTS, OHIO, ASSIGNOR OF ONE-HALF TO
UNITED STATES HOFFMAN MACHINERY CORPORATION, OF NEW YORK, N. Y., A
CORPORATION OF DELAWARE, AND ONE-HALF TO THE AMERICAN LAUNDRY
MACHINERY COMPANY, OF CINCINNATI, OHIO, A CORPORATION OF OHIO

PRESSING MACHINE

Application filed October 30, 1926. Serial No. 145,336.

This invention relates to power operated laundry pressing machines and has especial reference to the light rapidly actuatable type of press known as "full automatic" in operation wherein the cycle of the movable pressing member is completed entirely by power, although controlled at all times by the operator of the press; and particularly to the type wherein a work holding and guard member 10 provided with a pressing surface adapted to contact with the work is interposed between the pressing members.

The invention has for its object the provision in a press of the type to which reference has been made, of a combined guarding 15 and pressing member as described, an arrangement of the same as to construction, location and operation wherein the utmost advantage is obtained of the guarding feature 20 without impeding the most natural manner of operation of the press: the ultimate object of the invention being a press capable of extreme rapidity and ease of operation, entirely power actuated, yet operable with a 25 minimum of risk of injury.

Further objects of the invention will be apparent from the following description taken in connection with the accompanying drawings in which examples of my invention are 30 set forth as applied to representative pressing machines, and in which Fig. 1 is a side elevation of a machine chosen for illustration; Fig. 2 is a detail of a portion of the controlling mechanism employed, taken generally along 35 the line 2—2 of Fig. 1; Fig. 3 is a diagrammatic view of the control system employed; Fig. 4 is a side elevation of another machine with my invention applied thereto, parts not shown being identical with those of the machine appearing in Fig. 1, and Fig. 5 is a 40 plan view of the machine of Fig. 4.

The principal parts of the press are the base or frame 1, upon which is mounted a padded buck 2, and which is provided with 45 an upstanding arm 3 on which is pivoted at 4 an arm or pair of arms 5 carrying a head 6 adapted to close upon the buck by a mechanism to be described, and provided with a pressing surface corresponding in conformation 50 with that of the buck.

Mounted upon a bracket 7 projecting from the base 1 is a motor 8 directly connected through a worm or wheel mechanism not shown, with a crank 9 movable about a center 10, the outer end 11 of which is connected 55 by the rod 12 with a toggle joint 13 formed between the two links 14 and 15. The outer end of the link 14 is movable about a pivotal connection with the base as indicated and the upper member 15 is positioned by a swivel 60 block 16 carried or mounted upon the rearwardly extending portion of the pressing head arm 5.

Obviously by the mechanism described, 65 energization of the circuits of the motor 8 will cause rotation of the crank 9 and effect straightening of the toggle described, and thereby closing of the head 6 upon the buck 2; continued operation of the motor similarly alternately opening and closing the pressing 70 members. A spring 17 is mounted upon the toggle member 15 between the swivel block 16 and a fixed collar 18, whereby the member is made slightly yielding in compression so that pressure may be effected between the 75 pressing members subsequent to the closing of the same in a manner well known in the art; a cap 52 being secured upon the end of the member 15, whereby the toggle mechanism and the weight may co-operate therewith 80 returning the head to open position. A magnetic brake 19 is provided upon the motor shaft actuatable by mechanism within the box 20; and a timing switch 21 is mounted within a casing 22 whereby the motor may be automatically controlled during the pressing cycle 85 in a manner to be described; but the details of construction of the brake and timing switch, both of which are well known in the art and immaterial here, are not shown, except 90 diagrammatically in Fig. 3.

Mounted upon a lever 23 pivoted upon the arm 3 concentric with the arm 5 is a combined guarding and pressing or plate member 24. The plate 24 may be of sheet metal relatively 95 thin in section, extends between the pressing members throughout their pressing surfaces and is of conformation to fit exactly between the pressing surfaces upon closing of the pressing members. An upstanding portion 100

25 perforated as at 26 extends around the forward portion of the plate, the portion interposed between the pressing surfaces being smooth, and preferably highly polished. It is evident that the lower surface of the member 24 will in the pressing operation actually contact with the work laid upon the buck 2, and the buck and head being heated as is customary in the art, heat will be transmitted to the work from the head 6 through the plate during the pressing operation.

The upstanding portion 25 performs the function of a guard as well as a heat radiating or heat dissipating device for the plate so that the temperature of the plate is not excessive and will not injure the operator should it touch the fingers in the clamping of the work.

The various parts of the pressing machine are represented in Fig. 1 in what is known as the full open position, that is, the movable head 6 is raised from the buck to approximately the maximum extent possible.

Movement of the plate member 24 between the pressing members is controlled separately from that of the head although subject to movement of the head, by a pedal 27 pivoted upon the frame at 28 and connecting by a link or push rod 29 with a rearwardly extending portion of the lever 23, downward movement of the pedal thus effecting corresponding movement of the guard member. The plate and pedal are normally retained in the position illustrated by a tension spring 30 connected between suitable eyelets upon the arm 3 and lever 23 respectively. The upper extreme position of the plate is limited as by the set screw 31 immediately effective upon the pedal lever 32, to a position well clear of the extremely opened head member 6, the purpose of this arrangement being to allow radiation during non-press portions of the cycle, of the heat induced in the plate during the pressing operation.

The push rod 29 is formed in two pieces, the upper portion 29' extending downwardly into the hollow interior of the lower portion 29''. A compression spring 35 is positioned upon the portion 29' between a flange 36 thereon and a similar flange 36' upon the upper extremity of the lower portion 29'' of the push rod; a set screw 37 laterally extending into the stem of the upper portion 29' movable longitudinally in a suitable slot in the lower portion 29'' limits the effect of the spring 35.

The proportions of the plate member actuating mechanism are such that maximum depression of the pedal 27 will effect lowering of the plate upon the buck, and some slight pressure therebetween due to compression of the spring 35 between the flanges 36 and 36'; this pressure being just sufficient to maintain the work as positioned until the actual pressing pressure is effected subsequent to lower-

ing of the head 6 by the power mechanism.

Extending adjacent the forward portion of the lever 32 is a latch lever 38 provided with a cam surface 39 and urged about its axis 40 by the spring 41 to contact with the lever 32. Upon the side of the lever 38 is a notch adapted to receive and securely hold the lever 32 when lowered sufficiently, by engagement with the cam surface 39, to move the lever 38 in a clockwise direction, (Fig. 2) and pass into the notch.

Secured by a lost motion connection with the free end of the lever 38 by a slotted link 42 is a switch lever 43 enclosed within a switch box 44 and adapted to complete a circuit across contactors 45 in the upper position of the pedal 27 and across contactors 46 in the lower or latched position of the pedal.

The timing mechanism within the casing 22 may comprise a pair of contact segments 47 and 48 movable with the crank 9 in a counter clockwise direction and connected in the motor circuit as indicated in Fig. 3. A pair of contact arms 49 and 50 are arranged as indicated to rest alternately each upon its respective contact segment 47 or 48, the segment 47 corresponding with the closing movement of the press and the segment 48 corresponding with the opening movement of the press, the motor being arranged to run only in one direction. The contactors 45 are in the circuit of the contact arm 49 and the contactors 46 are in circuit with the contact arm 50. A treadle 51 is movable with the latch member 38 whereby depression of the treadle 51 may release the latched lever 32 to the action of the spring 30.

Operation of the press described will be as follows, assuming the parts initially in the position indicated in the figures. After smoothing the work upon the buck 2 the operator depresses the treadle 27 bringing the plate member 24 gently down upon the work to hold it in position, at the same time manually releasing the work. The upstanding portion 25 of the plate thereupon assumes a position substantially obstructing the opening between the pressing members. If readjustment of the work is desired, release or partial release of the treadle 27 will effect raising of the plate; the lever 32 moving merely upon the vertical portion of the latch member 38.

Upon satisfactory laying of the work, complete depression of the pedal 27 effects pressure of the plate upon the work to hold it in position, and moves the switch lever 43 to close the motor circuit at the contacts 46. Upon closing of contacts at 46 the brake 19 is magnetically released and the motor will start, operating the mechanism as described to close the head 6 upon the buck, and subsequent to closing effect pressure upon the work between the plate and the buck.

As the closing operation of the cycle pro-

gresses the contact segments 47 and 48 revolve until as maximum pressure is applied upon the work the contact segment 47 runs out from under the contact arm 50 stopping the motor and allowing spring actuated application of the brake 19.

Pressure upon the work continues until depression of the pedal 51 which releases the pedal 27 and allows return of the switch 10 arm 43 to again make contact at 45. This completes a motor circuit through contacts 45, contactor arm 49 and contact segment 48, restarting the motor and operating the pressing mechanism to return the head 6 to its open position, whereupon the segment 48 runs from under the contact arm 49 and the motor again stops. During the opening of the pressing members the plate member 24 follows the head 6 until attaining the 20 position illustrated whereupon the head continues to its uppermost position.

Figs. 4 and 5 disclose the pertinent portions of another construction of a generally similar type of press to which my invention 25 has been applied, parts not appearing in these figures being identical with those of Figs. 1 to 3. In this press the toggle member 15 forms a push rod as before, the upper end of which is positioned in a corresponding bore 30 in a swivel block 16 but the cap 52' in this case instead of being secured upon the end of the push rod is mounted for rotational movement upon the rearwardly extending portion of the arms 5 co-axial with the swivel block 16 whereby the inner or bearing surface 35 52'' of the cap may be swung into or out of alignment with the push rod 15 so as to control the effectiveness of the upward thrust of the rod upon the head of the press, the weight 53 being sufficient to cause the member 5 with the parts carried thereby to follow downward movement of the push rod 15 to the position shown in Fig. 4.

The push rod 15 in this case is formed in 45 two telescoping sections in a manner similar to the arrangement of the push rod 29 the spring 17 being positioned between collars 15' and 15'' on the two members, and of strength whereby the push rod functions 50 generally as a solid unit but is capable of yielding longitudinally during the actual pressing operation.

Carried upon a suitable lever movable with the cap 52' is a swivel block 53 in which is 55 loosely mounted a pull rod 54 the upper end of which is in pivotal connection with the rear extremity of the lever 23. The lower end of the pull rod is threaded to receive an adjusting nut 55 adapted upon raising the 60 pull rod a predetermined distance, to engage the swivel block 53 and raise the cap 52' to alignment or abutting position with respect to the end of the push rod 15. The proportioning and adjustment of the parts is such 65 that when the pressing head is substantially

raised away from the buck the action of gravity will tend to maintain the cap 52' in the position illustrated in Fig. 4. The lost motion between the nut 55 and the swivel block 53 is such that movement of the cap 52' to its push rod abutting position will not take place until the plate 24 is substantially closed upon the buck. The result is obviously that actuation of the motor will be effective to close the head 6 upon the buck 75 contingent upon substantially closing of the plate upon the buck; the electrical interlock including the contacts 46 as already described as well as the mechanical interlock including the cap 52', being operative to this 80 end.

What I claim is:

1. In a pressing machine of the type described, a pair of cooperative pressing members relatively movable in a plane to widely 85 separated relation, a plate substantially co-extensive with and movable between said pressing members, means for urging said plate to an idle position near to but out of contact with one of said pressing members, 90 an upstanding portion carried by said plate and adapted for obstruction of the opening between said pressing members when in said work securing position, power means for operating said pressing members, a controller for said power means, an operative connection between said controller and said plate, and an operator operated device connected to said plate for controlling the movement thereof. 100

2. In a pressing machine of the type described, a pair of cooperative pressing members relatively movable in a plane to widely separated relation, a plate substantially co-extensive with and movable between said pressing members, means for urging said plate to an idle position near to but out of contact with one of said pressing members, and being adapted for movement in advance of closing of said pressing members to a 110 work securing position upon one of said members, and adapted in said work securing position for transmitting heat and pressure from the other of said members for ironing said work, an upstanding portion adapted for obstruction of the opening between said pressing members when in said work securing position, power means for operating said pressing members, a controller for said power means, connections between said controller 115 and said plate, a pedal operatively connected to said plate, connections between said plate and pedal adapted to effect closing of said pressing members dependent upon positioning of said plate to secure said work, a latch member adapted to automatically engage said pedal in work securing position, and an operator operated means for releasing said latch. 125

3. In a pressing machine of the type described, a pair of cooperative pressing mem- 130

bers relatively movable in a plane to widely separated relation, a plate substantially co-extensive with and movable between said pressing members, said plate being adapted for securing work positioned upon one of said members, and for transmitting pressure from the other of said members for ironing said work, power means for operating said pressing members, a pedal operatively connected to said plate, a controller for said power means, a connection between said controller and said plate, means for automatically deenergizing said power means upon completion of the pressing operation, an operator operated member adapted to effect opening of said pressing members, a push rod operatively connected between said power means and one of said pressing members to move the same upon the other to effect the pressing operation, a cap carried by one of said members and movable to connect said push rod to or disconnect said push rod from operative relation with said movable pressing member, and a connection between said cap and plate whereby said push rod is maintained ineffective upon said pressing member subject to positioning of said plate to secure said work.

4. A pressing machine of the type described, a pair of pressing members relatively movable in a plane to widely separated relation, power means operatively connected to said pressing members for closing the same and applying power pressure to the work therebetween, a work clamping plate co-extensive with the pressing faces of said members and supported for movement therebetween, a controller for said power means, and operative connections between said plate and said controller.

5. In a pressing machine of the type described in claim 4 wherein the plate is provided with an operator operated device for moving said plate to work clamping position.

6. A pressing machine of the type described in claim 4 wherein the plate is provided with a heat dissipating means.

7. In a pressing machine, a frame, a stationary pressing member, a movable pressing member, a work holding and ironing plate co-extensive with the pressing areas of said members and movably mounted therebetween, power means, operative connections between the power means and the movable pressing member, a controller for the power means, an operator operated device for moving said plate, connections between said plate and said controller for effecting the operation of the controller by movement of said plate, and means normally tending to urge said plate to a position near to but out of contact with the movable pressing member when the press is open.

8. A pressing machine as in claim 7 wherein the operator operated coupling device is

arranged in the connections between the power means and the movable pressing member.

9. A pressing machine as in claim 7 wherein the operator operated coupling device is arranged in the connections between the power means and the movable pressing member, and connections between said coupling device and plate.

In testimony whereof I hereby affix my signature.

BLUFORD W. BROCKETT.
